(57) **CLAIM**

I claim the ornamental design for a bell base, as shown and described.

DESCRIPTION

FIG. 1 is a front perspective view of a bell base showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front end view of the bell base in accordance with my design, shown in its environment thereof.

The broken lines shown illustrate portions of the bell base that form no part of the claimed design.
